UNITED STATES PATENT OFFICE.

WILLIAM A. HUELDONK, OF JOLON, CALIFORNIA.

DREDGER AND EXCAVATOR.

No. 921,252.

Specification of Letters Patent.

Patented May 11, 1909.

Application filed July 14, 1908. Serial No. 443,411.

To all whom it may concern:

Be it known that I, WILLIAM A. HUELDONK, citizen of the United States, residing at Jolon, in the county of Monterey and State 5 of California, have invented new and useful Improvements in Dredgers and Excavators, of which the following is a specification.

My invention relates to dredging and excavating apparatus, and pertains especially 10 to gold dredger and excavator, and mechanism whereby the barge or other support on which the excavating apparatus is built may be adjusted and elevated, so that concentrators can be operated on the same.

15 The invention consists of the parts and the construction and combination of parts as hereinafter more fully described and claimed, having reference to the accompanying drawings, in which—

20 Figure 1 is a side elevation, partly sectioned, of the dredger. Fig. 2 is a plan, sectioned along line $x-x$ of Fig. 1, of the same. Fig. 3 is an enlarged detail of ladder 17. Fig. 4 is an enlarged detail of member 19. Fig. 5 25 is a detail of sheaves. Fig. 6 is an enlarged detail of turning table and bearings connected with it.

A represents a barge or other suitable support of any appropriate size, shape or construction.

Under the modern system of mining by dredgers, it is common to mount the excavating apparatus on a barge, as here shown, and to float this barge in a body of water, 35 elevating the material, and then running it off to land, where the concentrators are usually mounted, it being absolutely essential to successful concentration that the concentrators be maintained on a fixed level.

40 While I employ a barge, where a barge is needed, or applicable, I also devised means by which my concentrator has been mounted direct upon the barge, and the process of concentration successfully carried on upon the 45 barge in juxtaposition to the excavating means. To this end I mount at each corner of the barge a vertical spud 2 running in suitable guides 3 on the frame, and each spud has a rack 4 engaging a gear 5 which is actuated 50 through suitable connections from the hand-wheel 6. The lower end of the spud is preferably enlarged considerably, as indicated at 7, so that a broad foot-piece is provided for each spud, and which foot-piece is adapted to

rest on the bed rock and to sustain its share 55 of the load.

When the barge is located in suitable position for the dredging operations, shortly to be described, the spuds are run down and the hand-wheel 6 operated until the barge is practically supported on the spuds. The gearing of the hand-wheel 6 is such that a man can easily turn the latter and raise or lower that portion of the apparatus until the barge is level, so that the concentrators, which are 60 represented at 8, are properly adjusted so as to perform their functions in the desired manner. The material for the concentrators is delivered by the buckets 9 on to a sluice 10, thence successively on to the screens 11 and 12; the 70 tailings being discharged at the rear by the tailings dump 13.

The excavating buckets 9 are of any suitable type, and mounted on the endless chain conveyer 14 which travels over the upper and 75 lower sprockets 15—16 carried on the ladder 17. This ladder is suitably mounted for adjustment upward or downward to any elevation, and also to any inclination, and is also adapted to swing from side to side, so as to 80 excavate in an arc across the bow of the dredger. These various adjustments and means for operating the excavating apparatus conjunctively with the concentrating devices and delivery means, and the means 85 for elevating the barge and concentrators, therefore constitute the essential features of the present invention.

The top of the ladder 17 is hung by the top bearing shaft 18 in a radius frame 19 which is 90 journaled to swing about a universal head mounted on the supporting timbers 20 on the barge. As here shown, this radius frame 19 is journaled at its inner end on sleeves 21, Fig. 6, said sleeves forming bearings for the 95 drive-shaft 22. These sleeves are mounted on the turn-table casting 23, which casting has a hub 24 turning in a fixed bearing 25 on the frame timbers 20. The hub 24 forms a bearing for the vertical shaft 26, the upper end of 100 which shaft carries the bevel gear 27 meshing a corresponding gear 28 on the shaft 22. Shaft 26 is stepped at its lower end in a suitable bearing 29 and carries a bevel gear 30 meshing a corresponding gear 31 on shaft 32, 105 which latter receives motion from any suitable source of power, as the engine 33 and belt connections 34. Shaft 22 carries a

sprocket 35 by which a chain 36 transmits motion to the shaft 18 to operate the excavating buckets 9 in the desired manner.

The lower end of the ladder 17 is adjustably supported from the banger 37 by suitable means, as the line or cable 38, which latter is suitably rove through blocks 39—40—41, Fig. 1, and carried thence back to a winding drum 42. This drum 42 carries a worm gear 43 on its shaft. Suitable connection with this gear 43 is had with a hand-wheel 44, by which the inclination, and also the raising and lowering of the ladder, may be effected from time to time, as required.

The pulleys 40—41 are carried at the outer end of a boom 45, which latter, as used in actual practice, is constructed in the shape of a triangular frame, which is journaled at the inner end at 46 coaxially with shaft 26, and with the flat or horizontal side of this boom frame provided with rollers 47 running on a circular trackway 48. The sidewise motion of the boom, for the purpose of moving the ladder and buckets to right or left in an arc across the bow of the dredger, is effected by any suitable means. Preferably, as here shown, the inner face of the trackway 48 carries a segmental rack 49 with which a pinion 50 is adapted to mesh; this pinion being mounted on a suitable shaft 51 journaled on the boom, and the shaft 51 having worm connections with a shaft 52, which latter is operated by chains 53 running to a counter-shaft 54 also journaled on the boom, this counter-shaft being operated by a hand-wheel 55.

The raising and lowering of the ladder is not entirely effected by the line 38, since the function of the line 38 is rather to vary the inclination of the ladder; although it is ordinarily necessary to pay out or wind up the line 38 some when the ladder is raised or lowered. The raising and lowering of the ladder is chiefly effected, and the weight of the ladder supported, by the line 56 which is connected to a drum 57 mounted on the boom frame and operated by a hand-wheel 58 and suitable worm connections shown; said line 56 running back around a direction sheave 59, and thence to the top of the mast 60 and through the sheave blocks 61—62; the lower sheave block being suitably connected, as shown, with the top of the ladder.

The material which is elevated by the buckets is delivered into the chute or grizzly 10 which has its upper end adjacent to the ladder suitably suspended from the outer end of the radius frame 19, and its lower end pivotally supported at 63 in alignment with the shaft 26. It will thus be seen that this delivery chute 10 is adapted to turn from right to left with the boom, and always maintain the receiving end in uniform relation to the buckets.

The outer end of the boom 45 and the top

of the mast 60 are suitably stayed and braced in any appropriate manner.

In operation, the barge A having been moved to position where it is designed to excavate, is elevated and supported in whole or in part on the spuds 2, independent of the water in which it is located, so that it becomes, in fact, a stationary platform or support, and with the concentrators properly leveled up. By suitably manipulating the lines 38—56 the dredging buckets are raised or lowered, and adjusted so as to operate closer to or farther from the barge. Power is then transmitted through shaft 26, chain 36, and suitable connections, as previously described, to operate the dredging buckets. As the dredging proceeds, the hand-wheel 55 is manipulated to cause the boom frame to swing gradually to one side and then to the other, as required. The material which is elevated is dumped on to the chute 10, and thence delivered over the screens 11 and 12 to the concentrating devices 8; the waste and tailings from the screens passing on to the tailings stacker 13.

Having thus described my invention, what I claim and desire to secure by Letters Patent is—

1. In an excavating and gold-saving apparatus, the combination of a barge, an excavating apparatus thereon, concentrating apparatus thereon, means for delivering the material to be concentrated from the excavating apparatus to the concentrating apparatus, and means for leveling up the barge and supporting it independent of the water in which it is moored.

2. In an excavating and gold-saving apparatus, the combination of a barge, an excavating apparatus thereon, concentrating apparatus thereon, means for delivering the material to be concentrated from the excavating apparatus to the concentrating apparatus, and means for leveling up the barge and supporting it independent of the water in which it is moored, said leveling means comprising spuds at the corners of the barge, with means on the barge for raising and lowering the latter on the spuds.

3. In an excavating and gold-saving apparatus, the combination of a barge, an excavating apparatus thereon, concentrating apparatus thereon, means for delivering the material to be concentrated from the excavating apparatus to the concentrating apparatus, and means for leveling up the barge and supporting it independent of the water in which it is moored, said leveling means on the barge comprising spuds at the ends of the barge, said spuds having enlarged ends forming supporting foot members, and rack and pinion mechanism for raising and lowering the spuds.

4. In a dredging apparatus, the combination of a suitable support, a boom pivotally

- mounted on the support, a ladder and excavating buckets with means connected with the boom for adjustably supporting the lower end of the ladder, a radius frame pivotally supported at one end in axial line with the pivot of the boom and pivotally connected at the outer end with the top of the ladder, and means for transmitting power to operate the buckets.
5. In a dredging apparatus, the combination of a suitable support, a boom pivotally mounted on the support, a ladder and excavating buckets with means connected with the boom for adjustably supporting the lower end of the ladder, a radius frame pivotally supported at one end in axial line with the pivot of the boom and pivotally connected at the outer end with the top of the ladder, means for transmitting power to operate the buckets, said support for the boom having a segmental trackway and a segmental rack, the boom having rollers running on the trackway and having a pinion meshing said rack, and means for operating the pinion to turn 25 the boom from side to side.
6. An excavating apparatus comprising a suitable support, a boom pivoted on said support, said boom comprising a framework having rollers to run on a trackway on the support concentric with the pivot of the boom, a segmental rack concentric with said pivot, mechanism carried by the boom including a pinion to intermesh with said rack for operating the boom back and forth, a radius frame above the boom and having its inner end pivoted to swing horizontally in unison with the boom, and also pivoted to swing in a vertical plane independent of the boom, and a ladder carried at the outer end of said radius frame, and means for raising and lowering the ladder.
7. An excavating apparatus comprising a suitable support, a boom pivoted on said support, said boom comprising a framework having rollers to run on a trackway on the support concentric with the pivot of the boom, a segmental rack concentric with said pivot, mechanism carried by the boom including a pinion to intermesh with said rack for operating the boom back and forth, a radius frame above the boom and having its inner end pivoted to swing horizontally in unison with the boom, and also pivoted to swing in a vertical plane independent of the boom, and a ladder carried at the outer end of said radius frame, and means operated from and carried by the boom for raising and lowering the ladder.
8. In an excavating apparatus, the combination of a suitable support, a boom pivoted thereon, a radius frame above the boom and turnable in a vertical plane in suitable bearings, said bearings mounted on a turn-table which is journaled in axial line with the pivot of the boom, a ladder carried on the outer end of the radius frame, an endless conveyer on the ladder, means for raising and lowering the latter, and means for operating said endless conveyer.
9. In an excavating apparatus, the combination of a suitable support, a boom pivoted thereon, a radius frame above the boom and turnable in a vertical plane in suitable bearings, said bearings mounted on a turn-table which is journaled in axial line with the pivot of the boom, a ladder carried on the outer end of the radius frame, an endless conveyer on the ladder, means for raising and lowering the latter, and driving connections for operating said endless conveyer, said driving connections for the conveyer including a shaft mounted on the turn-table, a second shaft concentric with said turn-table, and intermeshing gears on said shafts.
10. In a dredging apparatus, the combination of a barge, a boom pivoted thereon to swing from side to side, a vertically disposed shaft arranged in axial line above the pivot of said boom, said shaft having suitable bearings at the lower end provided with suitable power connections, the upper end of the shaft journaled in a turn-table, which latter is turnable independently of the shaft, a horizontal shaft journaled in said turn-table, bevel gears connecting said shafts, a radius frame journaled to turn in a vertical plane about said horizontal shaft, a ladder pivotally connected with the outer end of said radius frame, an endless conveyer on said ladder, connections between said conveyer and said horizontal shaft for operating the conveyer, and connections with operating means on the boom for adjusting the ladder.
- In testimony whereof I have hereunto set my hand in presence of two subscribing witnesses.
